United States Patent Office.

JOSEPH STEGER, OF NEW YORK, N. Y.

Letters Patent No. 73,764, dated January 28, 1868.

IMPROVED CAR-STARTING APPARATUS.

The Schedule referred to in these Letters Patent and making part of the same.

TO ALL WHOM IT MAY CONCERN:

Be it known that I, JOSEPH STEGER, of New York, 82 Beekman street, in the county and State of New York, have invented a new and useful Improvement in Starting-Gear for Cars and Wagons; and I do hereby declare that the following is a full, clear, and exact description thereof, which will enable those skilled in the art to make and use the same, reference being had to the accompanying drawing, forming part of the specification, in which drawing—

Figure 1 represents a longitudinal vertical section of this invention.

Figure 2 is an inverted plan of the same.

Similar letters indicate corresponding parts.

This invention consists in a lever-pawl which has its fulcrum on an eccentric wrist-pin secured in the side of a drum, or which is otherwise attached to a shaft on which is mounted a drum, from which a rope or chain extends to the traction-bar of the car or wagon, said traction-bar being permitted to slide in a longitudinal direction, in combination with a ratchet-wheel mounted on the axle or secured to one of the wheels, in such a manner that when the lever-pawl is thrown in gear with said ratchet-wheel and a strain is exerted on the traction-bar, this strain is multiplied in proportion to the difference between the radius of the drum on which the draught-chain or rope winds, and the distance of the connection of the lever-pawl from the centre of its motion, and by these means a powerful and effective starting-gear is obtained.

A represents the truck-frame of a railroad-car or wagon, said truck-frame being supported by four, (more or less,) wheels, B, which are mounted on axles, C. On each of these axles is secured a ratchet-wheel, D, one only being shown in the drawing, which may either be mounted directly on the axles or rigidly connected to one or both wheels. From each end of the truck extends a platform, E, and under this platform is secured a shaft, F, on which is mounted a drum, G. From this drum extends a rope or chain, a, one end of which is secured to the circumference of the drum, while its other end is attached to the traction-bar H, which is permitted to slide in a longitudinal direction, so that by pulling said traction-bar out, a partial revolving motion is imparted to the drum G and shaft F. From the side of the drum G projects a wrist-pin, b, which forms the fulcrum for the lever-pawl I. If desired, said eccentric wrist-pin may be connected to the shaft F in any other desirable manner. The inner or working end of the lever-pawl I is subjected to the action of a spring, c, which has a tendency to raise the same clear of the circumference of the ratchet-wheel, and also to pull it back in the direction of the arrow marked thereon in fig. 2, while the other or tail end of said lever-pawl bears on a tilting-lever, J, which is subjected to the action of the foot-button d. This button is in convenient reach for the feet of the driver, and by depressing said button, the lever-pawl is thrown in gear with the teeth of the ratchet-wheel. If a strain is exerted on the traction-bar after the lever-pawl has been thrown in gear with the ratchet-wheel, this strain is multiplied in proportion to the difference between the radius of the drum G and the distance of the wrist-pin b from the centre of the shaft F, and the operation of starting the car or wagon is materially facilitated. As soon as the strain on the traction-bar ceases, the lever-pawl is thrown out of gear with the ratchet-wheel and carried back to its original position by the action of the spring c ready for a new operation.

Instead of securing the lever-pawl on the wrist-pin, it may be attached to one or more chains, which wind on the shaft itself; or on a drum of smaller diameter than the drum G.

The chain or rope a is kept taut by a spring, e, which bears on the traction-bar H. This spring is comparatively weak, so that it allows the traction-bar to recede by the action of the spring c, and at the same time the traction-bar is rendered yielding, so that when two cars run close against each other, the ends of the traction-bars, which form the buffers, will recede, and injury to these parts will be avoided.

The lever-pawl I may also be provided with a projection or cam, f, which bears against a spring-arm, g, or against any suitable abutment, so that as soon as the traction-bar and pawl are drawn out, said pawl is automatically depressed and thrown in gear with the ratchet-wheel, and as the pawl recedes it rises again, and the entire gear operates without requiring any attention.

What I claim as new, and desire to secure by Letters Patent, is—

The springs c e, in combination with the traction-bar H, rope or chain a, lever-pawl I, drum G, and ratchet-wheel D, all constructed and operating substantially as and for the purpose set forth.

This specification signed by me, this 2d day of December, 1867.

JOSEPH STEGER.
